GRINDING MACHINE

Pliny Catucci, Kearny, N. J., assignor to William
Crabb & Company, Newark, N. J., a corporation
of New Jersey

Application April 21, 1945, Serial No. 589,511

2 Claims. (Cl. 51—79)

1

This invention relates to a device for sharpening or pointing short rods or pieces of wire. It relates more specifically to an automatic grinding machine of this character which is particularly suitable for sharpening phonograph needles very rapidly and uniformly.

In carrying out the invention the blanks are not necessarily fed to the machine at a uniform rate but the extent of grinding each one is correct and the manner of grinding is controllable.

The invention may be understood from the description in connection with the accompanying drawings in which

Fig. 1 is a plan view taken perpendicularly to the base of the machine;

Fig. 2 is a side view partly broken away;

Fig. 3 is a side view from the opposite direction to Fig. 2;

Fig. 4 is a section along line 4—4 of Fig. 1 with parts removed;

Fig. 5 is a section along the line 5—5 of Fig. 1;

Fig. 6 is a section along the line 6—6 of Fig. 1;

Fig. 7 is a section through some of the shafts of a machine showing gears;

Fig. 8 is a section along the line 8—8 of Fig. 1;

Fig. 9 is a section along the line 9—9 of Fig. 1;

Fig. 10 is a section along the line 10—10 of Fig. 1;

Fig. 11 is a plan view of portions of the device shown in Figs. 5 to 10, being on an enlarged scale, 30 and

Figs. 12 and 13 are sections showing some details on greatly enlarged scale.

Reference character 1 indicates a floor or other support to which the base 2 of the machine is attached by means of lugs 3 and bolts 4.

A driving motor 5 is provided with grooved pulleys 6 and 7 on the shaft of the motor, pulley 6 being smaller than the pulley 7. A belt 8 extends from pulley 7 to a pulley 9 (Figs. 1, 3 and 4) attached to the transverse shaft 10 which has a shoulder 11 and a clamping hub 11' (Figs. 4 and 11).

The belt 12 extends from the pulley 6 to a pulley 13 that is attached to the transverse shaft 14, this belt passing under idler pulley 15 that is adjustable for tightening this belt. The shaft 14 is journalled in bearings 16 that are attached to one end 17 of the machine, this shaft being kept in place by means of collars 18 and set screws 19. A pulley 20 is attached to the other end of the shaft 14 with a belt 21 extending from this pulley and passing under a fixed pulley 22 and an adjustable pulley 23, adjustable as shown at 23', and around pulley 24 on shaft 25 which is jour-

nalled in an adjustable yoke 26 that is pivoted in bearings 27 in a bracket 28 that is attached to the frame 2 of the machine. The shaft 25 carries a friction wheel 30. This wheel and the pulley 24 are secured to the shaft 25 by collars 31 and 32 respectively that are provided with set screws (Fig. 2). Friction material 33 is provided around the periphery of wheel 30. A lever 34 that is pivoted on the bracket 28 is adapted to be pressed against a projection 35 on yoke 26 to swing the wheel 30 away from contact with the wheel 37 when desired. A spring 36 normally keeps wheels 33 and 37 in contact. The wheel 37 (Figs. 1, 2 and 6) is attached to shaft 38 by set screws 40 and is provided with friction wear material 41 on the outside with which the friction material 33 on wheel 30 can be brought into contact. A housing 43 (Figs. 1, 2, 3 and 6) which serves as a bearing for shaft 39 is attached to the frame 2 of the machine. A bevel gear 44 (Fig. 6) is screwed to the end of the shaft 39 and meshes with a bevel gear 45 within the housing 46 which has a removable cover 47. The shaft 39 is journalled in bearings 48 and 49 and is kept in place by collars 50 and 51.

The bevel gear 45 in housing 46 (Fig. 9) is axially aligned with and is securely connected to gears 51 and 52. These three gears are carried by shaft 53 that is journalled in bearings 54 and 55 in opposite walls of the housing 46. The gear 51 meshes with a gear 56 on shaft 57 that is kept in place by an adjustable set screw 58 and a collar 59. The shaft 57 extends into the housing 6 as shown at 61 in Figs. 8 and 9. The member 60 has a projecting lip or flange 60' (Fig. 8).

The gear 52 (Fig. 9) on shaft 53 meshes with gear 62 on shaft 63 that is kept in place by set screws 64 and collar 65. This shaft 63 also extends into the casing 60 as shown at 66. Removable screws 67 retain the cover of casing 60 in place. The portions 61 and 66 of shafts 57 and 63 are provided with spiral guides 69 and 70 (Figs. 8, 9 and 11) that are rectangular in cross-section, these guides being adapted to align the pieces of wire or the like that are to be correctly fed to the grinder 82.

A supporting and guide plate 72 (Figs. 4 and 9) for wire or the like to be sharpened or pointed, 50 has an arcuate portion 73 with a radius of curvature corresponding to the outer surface of the needle-holding and rotating wheel 75 which is mounted on shaft 76 by which it is rotated. The wheel 75 has a middle portion (Figs. 9 and 12) of 55 rubber or similar material that is kept in place

between metal discs 78 and 79 that may be clamped together by bolts 80.

The grinding wheel 82 (Figs. 4, 9, 11 and 12) is mounted on the driving shaft 10 and has a transversely curved grinding surface 83 (Fig. 4).

Housings 85 and 86 (Fig. 4) are provided for ball bearings 87 for shaft 10. These housings are adjustable to move the shaft 10, grinding wheel 82 and housings 85 and 86, the housings 85 and 86 being moved laterally and the wheel 82 radially. Guide supports 88 and 89 are provided for the bearings 85 and 86. Worm gears 92 and 93 are hand-operated by a screw threaded rod 94 having a handle 94' for positioning the shaft 10 laterally and the wheel 82 radially. A worm gear 95 on shaft 10 meshes with the gear 96 on transverse shaft 97, the gears 95 and 96 being enclosed in a housing 98 in which bearings such as bearing 99 are provided. The shaft 97 extends through the housings 98 and 100 (Figs. 1, 4 and 5) and is journaled in bearing 101 of housing 98 and in the lower end of link 102 (Figs. 1 and 5) that is pivoted at 103 on arm 104. A support 106 (Figs. 1 and 5) is provided for the arm 104. This support 106 is provided with a rib 107 along which arm 104 is longitudinally adjustable. The arm 104 is held in adjusted position by bolt 108. A tongue and groove connection 109 connects the support 106 with the frame 110 of the machine so that it is adjustable longitudinally of the machine.

A bevel gear 112 on shaft 113 is driven by gear 114 on shaft 97 which is journaled in a bearing in housing 100.

An adjustable housing 115 is supported by the support 116 and is adjustable to different heights by means of the bolt 117. Bearings 120 are provided in the housing 115 between which the worm gear 121, which is keyed to shaft 113, is mounted. The gear 122 is provided on shaft 76 with which the worm gear 21 engages.

Adjustable cone-shaped bearings (Figs. 1 and 2) are provided for the shaft 76 in carriers 126 which are kept in adjusted positions by bolts 127 in said carriers. The bearings 124 are adjustable in height on brackets 130 that are in turn supported on the base of the machine. Plates 121 with holes for passage of the bearing 124 are attached by bolts 132 to the supports 126. Transverse U-shaped openings 135 are provided in the upper ends of the brackets 130 to accommodate the support 126. Bolts 136 with lock nuts 137 thereon limit the lower positions of the support 126 and bolts 138 with heads under plates 139 are held in place by screws that pass through openings in the transverse plates 140 and keep the supports 126 in place so that they do not get out of adjustment.

A feed plate 144 (Figs. 1, 8 and 11) has parallel grooves 145 in its upper surface, these grooves terminating along the line 146, with the upper surface of the remainder 147 of plate 144 made smooth and aligned with the outer surface of the roller 66 and the center line of the roller 61 (Fig. 8).

A lip or extension 148 of casing 60 almost touches the spiral guide 79 on roller 66. The plate 150 (Figs. 2 and 8) with dove-tail edges 151 receives the screw bolts 67 so that this portion of the device can be adjusted longitudinally to different distances from the wheel 75 and can be tightened in place by means of the bevel strip 152 and screws 153. It can be moved along the base member 155 to which the plate 156, upon which the feed plate 144 rests, is attached by

screw bolts 157. The feed plate 144 is attached to the plate 156 by screw bolts 158.

Wires 160, or similar devices such as phonograph needles to be ground or sharpened, are indicated in Figs. 8-13. A knob 164 (Figs. 12, 1 and 4) on an adjustable screw 165 is journaled in the bearing 166 in plate 167 which is anchored to the frame 2 of the machine and is prevented from moving longitudinally by collars 168 and 169. It carries a graduated disk 170 for adjustment purposes. The threaded end 171 of the screw 165 extends into a threaded lug 172 on plate 173 that is provided with a dove-tail shaped passageway 174 (Fig. 4) along its lower side in which the dove-tail shaped portion 175 of support 176 engages. The support 176 rests upon the base 2 of the machine. An opening 178 (Fig. 12) is provided in the plate 173. This opening receives a short metal nipple 179 to which a flexible hose or conduit 180 is attached. A shield 181 is attached to the plate 173 in front of the grinding wheel 82 above the opening 178.

A supporting member 184 (Figs. 12 and 13) is provided with an offset extension 186 for the needles 160 while they are being ground. The member 184 is provided with a shoulder 185 at the inner end of the extension 186. The upper surface of the extension 186 carries the curved portion 183 of the guide plate 72 (Figs. 4, 9 and 12) for the needles or the like 160 while they are being ground.

A chute 188 (Figs. 1, 2, 3 and 4) is provided for the finished or ground needles. It has an opening 189 along its upper side near the edge of the plate 173 to receive the ground needle and which extends outwardly sufficiently to clear the machine.

The operation is as follows:

The motor 5 with pulleys 6 and 7 is started. The shaft 10 carrying grinding wheel 82 (Figs. 4 and 9) is adjusted to the proper height or vertical position with respect to wheel 75 by turning the handle 94' of shaft 94 (Figs. 3 and 4). The grinding wheel 82 is also adjusted laterally of the wheel 75 (Fig. 12) by turning knob 164 so as to obtain the proper taper on the ground points of the wires or needles 160. The graduations 170, with a line or marker on plate 167, enable exact adjustment to be made.

The needles or wires 160 to be ground are fed to the plate 144 (Figs. 8 and 11) so that they slide downwardly along the parallel grooves 145 in this plate until the ends to be ground rest radially against the side of the extending end 61 (Figs. 8, 9 and 11) of shaft 57 between convolutions of the spiral guide 69, with an intermediate portion of each needle resting on the extending portion 66 of shaft 63 between convolutions of the spiral guide 70. The needles are then beyond the lower ends 146 of the ribs or grooves 145 (Figs. 1, 8 and 11) so that they lie upon the smooth surface 147 of plate 144 and are therefore then free to be moved laterally or parallel to the ends 61 and 66 of shafts 57 and 63 as shown in Fig. 11. The spirals 69 and 70 keep these needles parallel to each other and at right angles to the center line of the portion 61 of shaft 57.

They are thus moved laterally and parallel to each other to the edge of plate 144 whereupon the portion 77 of rubber or other yielding material on wheel 75 (Figs. 9 and 12) rolls them through the arcuate space between this wheel and the curved upper surface of plate 173 which is made of hardened wear-resisting material, thus keeping

them aligned and parallel to each other while they are being rolled along this curved surface. During this time the ends that are to be ground or sharpened are brought into contact with the revolving grinding wheel 82 while the other ends move freely along the fixed smooth surface 185 of fixed plate 184 (Figs. 12 and 13). The plate 72, 73 (Fig. 9) is made of hardened wear-resisting material and is backed by rigid material preferably of metal. The needles 160 are turned around their axes as they are rolled along the surface of plate 72 (Figs. 9, 12 and 13) while the revolving grinding wheel 82 grinds the ends thereof uniformly.

After the pieces 160 have been ground they 15 are carried farther along the plate 72 by the wheel 75 whereupon they enter the chute 188 and are carried outside of the machine.

The knob 164 and micrometer disc 170 (Fig. 12) on screw 165 enable the operator to adjust the grinding wheel 82 to the exact position needed for the correct amount of sharpening or grinding of the needles 160 and all of them can be automatically shaped exactly alike. It will be clear from Figs. 9 and 11 that the spiral guides 69 and 70 keep the needles 160 parallel to each other and at right angles to the portion 61 of shaft 57 so that they are properly aligned to be ground when they are carried along the plate 73.

The feeding of the needles can be quickly stopped while the machine is running by pressing downwardly upon the lever 34 (Fig. 1) thereby disengaging the driving wheel 33 from the wheel 37 which drives the gear 44 (Fig. 9) which in turn drives the shaft 57, 63 and spirals 69, 70. Even when no needles are being ground, the wheels 75 and 82 (Figs. 12 and 13) do not touch. The abraded material is thrown into the conduit 180 and carried away. The finished needles 160 drop into the open end 189 of conduit 188 and pass out at the right hand end of the machine (Figs. 1, 2 and 4).

The needle holding and turning wheel 75 is driven from motor 5 by pulley 7, belt 8, pulley 9 (Fig. 1), shaft 10 (Fig. 4), worm 95, worm gear 96, shaft 97, bevel gears 114 and 112 (Fig. 5) in

casing 100, shaft 113, worm 121, worm gear 122 in casing 115 (Figs. 1 and 5) and shaft 76. The grinding wheel 82 (Fig. 4) is also mounted upon and driven by the shaft 10 so that there is a constant rate of rotation of the wheel 82 compared to that of wheel 75.

The rate of feeding the work or articles 160 to the grinder 82 is not necessarily correlated to the speed of the wheel 82. The parts 160 may be caused to enter the feeding mechanism at any time. When the arm 24 is pushed down to disengage the wheels 33 and 37 or when there is some lost motion between them, no harm is done.

What is claimed is:

1. A grinding machine for sharpening the ends of rods and pieces of wire and the like which comprises a plate having parallel grooves therein for said rods or wire, revoluble spiral guides spaced from said grooves adapted to receive said rods or wire and move them laterally while maintaining them in parallel relation.

2. The device of claim 1 in which one of said guides is adapted to operate as a stop for limiting the longitudinal movement of said rods or wire.

PLINY CATUCCI.
